Specification for Design.

Patented Dec. 30, 1919.

Application filed July 5, 1919. Serial No. 308,901. Term of patent 14 years.

To all whom it may concern:

Be it known that I, AUGIE L. HANSEN, a citizen of the United States, residing at Evanston, in the county of Cook and State of Illinois, have invented a new, original, and ornamental Design for a Carbid-Cup for Acetylene-Lamps, of which the following is a specification, reference being had to the accompanying drawing, forming a part thereof.

The figure is a perspective view of a carbid cup showing my new design.

I claim:

The ornamental design for a carbid cup for acetylene lamps as shown.

In witness whereof, I hereunto subscribe my name this 1st day of July, A. D., 1919.

AUGIE L. HANSEN.
